UNITED STATES PATENT OFFICE.

FREDERICK F. BENNETT, OF YPSILANTI, MICHIGAN.

OIL BURNER.

Application filed October 13, 1924. Serial No. 743,484.

The invention relates to oil burners of the wick type and has for its object the obtaining of an improved construction having certain novel features amongst which are first, 5 the provision of an improved casing or container for the burner which is entirely leak-proof; second, the provision of an improved construction of a wick actuator and third, the provision of a novel clamping arrangement for the oil inlet tube. These and other 10 features of construction are more fully set forth in the detailed description hereinafter given and illustrated in the accompanying drawings wherein:

15 Figure 1 is an elevation of the burner with certain parts thereof shown in section;

Figure 2 is a longitudinal section through the axis of the burner;

20 Figure 3 is a plan view thereof with parts broken away.

The improved burner comprises a cast metal casing 1 having the inner and outer tubular portions 2 and 3 respectively forming an annular chamber 4 therebetween and 25 integrally connected by means of the bottom wall 5. The inner tubular portion is of lesser length than the outer member and is provided with a machined top surface 6 while within the tube there are the upper 30 and lower cross members 7 and 8 respectively, the upper member being provided with a threaded aperture 9. The outer tubular portion 3 of the casing is preferably of slightly larger circumference at the bottom portion thereof, as indicated at 10, and 35 has an annular supporting flange 11 and the top flange 12. The upper portion of the outer tube 3 is provided with the smoothly finished internal annular surface 13 for 40 guiding the tubular perforated wick supporting member 14 to which is fastened the annular wick 15.

45 16 is a removable cylindrical sheet metal structure insertable within the annular chamber 4 to form the inner guide for the annular wick and as shown, is provided with a cup-shaped head 17 centrally apertured at 18 to permit the clamping screw 19 to pass therethrough and engage the threaded aperture 9. The head 17 is strengthened by the 50 downwardly turned flanges 20 thereby increasing the rigidity of the central cross member 21 of the head. The removable tubular structure 16 forms an inner guide for 55 the annular wick and by reason of its removability the assembly and disassembly of the

wick in the burner is facilitated. Preferably the member 16 is provided with a series of bracket stops 21' arranged around the periphery of the cylindrical outer surface 22 to 60 form means for limiting the rise of the wick above the top surface 23 of the outer casing 1.

At one side of the casing 1 there is formed 65 an integral housing 24 provided with a longitudinal bore 25 intersecting the annular chamber 4 in an aperture 26. The housing is interiorly threaded at 27 to receive a threaded plug 28, said plug being soldered or otherwise suitably secured to a tubular housing 29. This housing forms the bearing for the rod 30 having the gear wheel 31 at its lower end extending through the aperture 26 into the annular chamber 4 and meshing with the diagonally aligned perforations 32 70 in the wick supporting member 14. The upper end of the rod 30 has secured thereto, a knob 33 which forms the handle for adjusting the wick.

In order to remove the wick actuating 75 mechanism from the burner casing it is only necessary to unscrew the plug 28 from the housing 24, after which the tubular housing may be moved laterally to disengage the gear wheel 31 from the perforations 32 and 80 then withdrawn outwardly through the housing 24, the entire actuating mechanism being removed as a unit.

In order to clamp the oil inlet tube 34 to 85 the oil burner, I have formed the outer casing with an integral U-shaped bracket 35 having the threaded aperture 36 therein in alignment with the conical inlet aperture 37 in the bottom member 5 of the casing. The oil inlet tube is provided with a conical nipple 38 preferably secured thereto by soldering or some other means forming a leak-proof joint, this nipple being insertable in the conical aperture 37 and adapted to be 90 secured thereto by tightening of the setscrew 39 threadedly engaging the aperture 36 and contacting with the oil inlet pipe 34 at a point diametrically opposite to the nipple 38. The bracket 35 is of substantial height to permit the pipe 34 and the nipple 95 to be inserted in and removed from the bracket and this construction therefore permits quick attachment and detachment of the oil burner from the inlet pipe.

100 What I claim as my invention is:

1. An oil burner comprising a cast metal container having a bottom portion and

spaced inner and outer cylindrical walls integral with said bottom portion forming an annular oil-receiving chamber therebetween, a cylindrical member within said annular 5 chamber and spaced from said outer wall to form an annular wick chamber between said member and outer wall, an annular wick in said wick chamber, an annular wick-supporting member having helically arranged 10 perforations therein, and means for adjusting said wick.

2. An oil burner comprising a cast metal container having an annular oil-receiving chamber therein, a cylindrical member 15 within said annular chamber spaced from the outer wall thereof to form an annular wick chamber between said member and outer wall, an annular wick within said chamber, and means for adjusting said wick 20 in said wick chamber.

3. An oil burner comprising a cast metal container having a bottom portion and spaced inner and outer cylindrical walls integral with said bottom portion forming an 25 annular oil-receiving chamber therebetween, the outer cylindrical wall being of greater length than the inner wall and having a smooth guiding surface near the upper portion thereof, a cylindrical tube insertable 30 within said annular oil-receiving chamber and spaced from said outer cylindrical wall to form an annular wick chamber therebetween, means for clamping said cylindrical tube to said inner cylindrical wall, an annular 35 wick within said wick chamber, and means for rotatively and longitudinally adjusting said wick within said wick chamber.

4. An oil burner comprising a cast metal container having an annular oil-receiving 40 chamber therein, a boss at one side of said container formed integral therewith and provided with a cylindrical bore extending at an angle to the longitudinal axis of said container and intersecting said annular 45 chamber, a tubular wick within said annular chamber, an annular wick-supporting member secured to said wick and provided with a series of helically aligned perforations 50 therein, a tubular housing secured to said boss, a shaft journaled in said housing having a toothed wheel engageable in the perforations of said wick-supporting member, and a handle at the opposite end of said shaft for adjusting said wick.

5. An oil burner comprising a cast metal container having an annular oil-receiving chamber therein, a cylindrical tube within 55 said oil-receiving chamber forming an annular wick chamber therein, a wick-supporting member within said wick chamber having helically aligned perforations therein, a boss formed upon the outer surface of said container formed integral therewith and provided with a cylindrical bore extending 60 at an angle to the axis of said container and

intersecting said wick chamber, and adjusting mechanism for said wick insertable through said bore and comprising a nut 70 threadedly engaging said boss, a tubular housing secured to said nut, a shaft journaled in said housing and extending within said bore, an adjusting knob at one end of said shaft, and a toothed wheel at the opposite end of said shaft arranged to engage the perforations of said wick-supporting member.

6. An oil burner comprising a container having spaced inner and outer cylindrical walls and a connecting bottom portion integral therewith forming an annular oil-receiving chamber, a cylindrical member within said annular chamber spaced from said outer wall to form an annular wick chamber, and an annular wick in said wick chamber adapted for rotative and longitudinal 80 adjustment.

7. An oil burner comprising a one-piece container having an oil-receiving chamber therein, a cylindrical member insertable within said oil-receiving chamber and spaced from the outer wall of said container to form an annular wick chamber therebetween, and an annular wick longitudinally adjustable in said wick chamber and guided by said cylindrical member and the inner 90 surface of the outer wall of said container, the latter being accessible for machining when said cylindrical member is removed.

8. An oil burner comprising a cast metal container having a bottom portion and spaced inner and outer cylindrical walls integral with said bottom portion forming an annular oil receiving chamber therebetween, a cylindrical member within said annular chamber and spaced from said outer wall to 100 form an annular wick chamber therebetween. a head carried by said cylindrical member adapted to seat upon said inner wall and be secured thereto, said head being provided at its outer edge with a plurality of 105 spaced wick stops.

9. A wick actuating mechanism for an oil burner comprising an integral boss carried on the outside of said burner, provided with a longitudinal bore intersecting the interior of said burner, a closure member for said boss threadedly engaging the outer end thereof, said closure member provided with longitudinal bore and a tubular housing extending through said bore and secured to said closure member, a shaft sleeved in said housing carrying at its lower end a toothed wheel engageable with a wick supporting member of said burner, and carrying at its upper end an adjusting knob.

10. The combination with an oil burner having a cast metal container provided with a longitudinally bored boss integral therewith, of a wick actuating mechanism insertable in and removably secured to said boss 110

comprising a nut threadedly engaging said boss, a tubular housing extending through and secured to said nut, a shaft sleeved in said housing and extending into said boss, an adjusting knob secured to said shaft at its outer end and a toothed wheel carried by said shaft at its lower end in engagement with a wick supporting member of said oil burner.

- 10 11. An oil burner comprising a container having an oil receiving chamber therein, a wick supporting member within said chamber, a boss carried on the outside of said burner provided with a longitudinal bore intersecting said chamber, a shaft removably secured in said boss and a toothed wheel carried by said shaft projecting partially within said chamber and engaging the wick supporting member.
- 15 12. An oil burner comprising a container having an oil receiving chamber therein, a wick supporting member within said chamber, a boss carried on the outside of said burner provided with a longitudinal bore intersecting said chamber, a shaft within the boss, a toothed wheel carried by the said shaft projecting partially within the chamber and engaging the wick supporting member and means for removably securing the shaft and wheel within the boss including a nut engaging the outer end of the boss provided with a bore through which the said shaft is adapted to extend.
- 20 13. An oil burner comprising a container having an oil receiving chamber therein, a wick supporting member within said chamber, a boss carried on the outside of said burner provided with a longitudinal bore intersecting said chamber, a shaft within the boss, a toothed wheel carried by the said shaft projecting partially within the chamber and engaging the wick supporting member and means for removably securing the shaft and wheel within the boss including a nut engaging the outer end of the boss provided with a bore through which the said shaft extends, the relation between the boss and toothed wheel being such as to allow lateral movement of the wheel with respect to the boss for disengaging the wheel from the wick supporting member when the shaft and wheel are removed from the boss.
- 25

In testimony whereof I affix my signature.
FREDERICK F. BENNETT.
